VERNON D. LANDON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

RADIO RECEIVING SYSTEM.

Application filed April 2, 1924. Serial No. 703,669.

My invention relates to systems for the reception of radio signals.

One object of my invention is to provide a more convenient and more efficient means for the reception of radio-frequency signal energy.

Another object of my invention is to provide means comprising a plurality of triode thermionic discharge devices in connection with a radio receptor circuit, whereby regeneration of the energy received by the receptor circuit is accomplished by one triode to produce a minimum effective circuit resistance and the amplification and repeating of the signal is accomplished by a separate triode.

It has been found convenient for certain radio receiving purposes to separate the function of regeneration of a radio receptor circuit from the function of amplification of a received energy signal, as practiced in the prior art. My invention provides means whereby this may be accomplished.

Other objects and structural details of my invention will be apparent from the following description when read in connection with the accompanying drawing, wherein:

The single figure is a diagrammatic sketch of a radio receiving apparatus comprising my invention.

In the drawing, a radio receiving system comprises a radio receiving aerial 1, a series tuning condenser 2, a series tuning inductance 3 and a ground 4 connected thereto. A triode 5 has anode, cathode and grid electrodes and electric current supply sources are connected thereto. A coil 10 in inductive relation to inductance 3, is connected in the plate circuit of triode 5. The grid electrode of triode 5 is connected to the conductor between the condenser 2 and the inductance 3, and the cathode of triode 5 is connected to the conductor between the inductance 3 and the ground 4. By this means, the triode 5 is caused to furnish regenerating energy to the radio receptor circuit.

A triode 6, which is also provided, has its electrodes connected to the same current sources which furnish current for the triode 5, by suitable connections and resistance control means. The grid of triode 6 is connected to the same lead as is the grid of triode 5.

A radio-frequency transformer 7 is provided, having a number of coils. Coil 8 is the primary winding of the transformer and

is connected between the anode of triode 6 and the source of plate current. Coil 9 is connected to a terminal of coil 8 and to one terminal of a condenser 11. The other terminal of the condenser 11 is connected to the grid electrode of triode 6. The coil 9 and the condenser 11 in combination constitute a reversed feed-back means which prevents the triode 6 from either sustaining itself in oscillation or furnishing regenerative energy to any other portion of the circuit. The secondary of transformer 7 comprises a coil 12 which is shunted by a condenser 13.

The cathodes of triodes 14 and 15 are connected together and through a rheostatic control means to the previously mentioned supply of cathode heating current. Likewise, the grids of triodes 14 and 15 are connected together, and to one terminal of the secondary winding 12 of amplifier transformer 7.

The transformer 7 is equipped with a fourth coil 16 which is connected between the anode of triode 14 and the source of plate current, as indicated in the sketch.

A second amplifying transformer 17 is similar in construction to transformer 7, having four coils similar to the coils of transformer 7. Coil 18, which is the primary winding of transformer 17, is connected between the anode of triode 15 and the source of plate current. A second coil 19, also in inductive relation to coil 18, is connected between the coil 18 and a condenser 21. The second terminal of condenser 21 is connected to the grid of triode 15. The coil 19 and the condenser 21, as before, serve as a reversed feed-back means whereby triode 14 is prevented from sustaining itself in oscillation. Coil 22 is the secondary of transformer 17. It is shunted by a condenser 23 in a manner similar to the shunting of coil 12 by condenser 13.

The cathode of a detector triode 24 is connected to the source of cathode heating current. The grid of triode 24 is connected to a grid leak and a grid condenser combination 25, the other terminal of which is connected to a terminal of coil 22. The second terminal of coil 22 is connected to the cathode of triode 24. The anode of triode 24 is connected to the fourth coil 26 of transformer 17. The other terminal of coil 26 is connected to signal receivers 27 from which the circuit is continued by a conductor to the source of plate current. A condenser 28 is provided con-

nected between the second lead from coil 26 and the cathode lead of triode 24. The condenser 28 serves as a by-pass for radio-frequency energy in the plate circuit of triode 5 24 past the signal receivers.

In the operation of my device, signals are received upon aerial 1. The signals set up an oscillatory current in the aerial and its connected impedances when the constants of 10 the impedances are adjusted to bring the circuit into resonance with the arriving signals. Potential variations corresponding to the receiving signals are then impressed upon the grids of triodes 5 and 6 in the customary 15 manner.

The triode 5, by virtue of the inductive coupling between its plate coil 10 and the inductance 3 in the aerial circuit, furnishes regenerative energy to increase the amplitude 20 of the oscillatory current produced in the antenna and its connected resonant circuit. Energy from the same signals is likewise impressed upon the grid of triode 6, which energy is increased in amplitude by the regenerative action of the triode 5 and the connected coil 10.

The triode 6 impresses, through coil 8 in its anode circuit, amplified oscillatory energy upon the secondary coil 12 of transformer 7. 30 The presence of coil 9 and condenser 11, which together constitute a reversed feed-back, prevents the triode 6 from oscillating or tending to oscillate, thereby causing the triode 6 to have a purely repeating and amplifying action.

Energy from coil 12 is impressed upon the grids of triodes 14 and 15. The presence of coil 16 in inductive relation to coil 12, which is connected in the anode circuit of triode 14, 40 produces a regenerative action upon the energy received by coil 12, thereby increasing the amplitude of the oscillations impressed upon the grid of triode 15.

The presence of coil 18 connected in the 45 anode circuit of triode 15 causes the transfer of energy to coil 22 through transformer 17. As in the transformer 7, a reversed feed-back is provided, coil 19 and condenser 21 being the means for producing the reversed 50 feed-back which prevents the triode 15 from tending to oscillate. The energy transferred from coil 18 to coil 22 is impressed upon the grid of triode 24 by way of the grid leak and grid condenser 25.

The presence of coil 26 in the anode circuit 55 of the triode 24 gives a regenerative action from triode 24 as well thereby allowing maximum amplification and the production of maximum signal strength in receivers 27 60 which are connected in the anode circuit of triode 24.

By this means I am enabled to produce a 65 radio receiving system in which the functions of regeneration and the functions of amplification are performed by separate triodes,

thereby obtaining greater efficiency in amplification and greater accuracy of repetition.

While I have shown only one embodiment of my invention in the accompanying drawings, it is capable of various changes and 70 modifications without departing from the spirit thereof and it is desired, therefore, that only such limitations shall be imposed thereon as are indicated in the prior art or in the appended claims.

I claim as my invention:

1. A regenerative radio receiving system comprising a radio-frequency responsive circuit, and connected amplifying, detecting and signal reproducing means, said means comprising stages, said stages being arranged in cascade and the cascade couplings being only between the stages, each of said stages comprising a plurality of triodes and circuits, one of said triodes and its circuits constituting a regenerative device and another of said triodes and its circuits constituting a repeating device, said repeating device including means for preventing self-oscillation.

2. A regenerative radio receiving system comprising a radio-frequency responsive circuit, and connected amplifying, detecting and signal reproducing means, said means comprising stages, said stages being arranged in cascade and the cascade couplings being only between the stages, each of said stages comprising a plurality of triodes and circuits, one of said triodes and its circuits constituting a regenerative device, another of 90 said triodes and its circuits constituting a repeating device and said repeating device circuits comprising a reversed feed-back circuit.

3. A radio receiving system comprising in combination a triode having a feed-back circuit, a second triode having a reversed feed-back circuit and a direct, small-impedance connection between the grids of said triodes whereby said grids are always at the same potential.

4. A regenerative radio receiving system comprising in combination, a triode having a feed-back circuit, a second triode having a reverse feed-back circuit, and interlinking and cooperative circuits, said circuits including means whereby both the received signal and the result of feed-back are impressed on the grid of the second triode and thereby causing said triodes to cooperate in the amplification of signals.

5. In a radio device, a pair of vacuum tubes having their grids directly and immediately connected, means for rendering one of said tubes regenerative, and means for preventing regeneration of the other tube.

6. In a radio receiving system, a plurality of amplifying stages, each stage comprising a plurality of vacuum tubes, direct connections between the grids of the tubes of each stage, means whereby at least one of the tubes

of each stage may be rendered regenerative, and means whereby at least one of the other tubes of each stage is prevented from regenerating.

- 5 7. In a radio receiving system, a pair of thermionic devices having a common input circuit, each thermionic device having an individual output circuit, means for coupling the output circuit of one of said devices to

10 said common input circuit, in a sense to cause

regeneration, and means for coupling the output circuit of the other of said devices to said common input circuit in a sense to oppose regeneration of oscillations in said last-mentioned device.

15

In testimony whereof, I have hereunto subscribed my name this 27th day of March, 1924.

VERNON D. LANDON.
